CHUCK

William E. Powell, Westwood, Calif.

Application August 25, 1941, Serial No. 408,253

7 Claims. (Cl. 51—213)

My invention relates to new and useful improvements in chucks for holding a plurality of elements to be ground.

An important object of my invention is the provision of a device of essentially simple and compact construction that is operative to securely hold a plurality of blades or bits properly associated with each other and with a grinding tool so that all of the blades may be simultaneously shaped to a predetermined pattern.

Another object of my invention is the provision of a device of the above mentioned character that is highly efficient in its action to securely hold the blades and that will positively and automatically lock itself in the closed position until such time as it is released for renewal or turning of the blades.

Other objects and advantages of my invention, will be apparent during the course of the following description.

In the drawing, forming a part of this specification, and wherein like numerals are employed to designate like parts throughout the same,

Figure 1 is a side elevation of a device embodying my invention and showing parts broken away for clearness of illustration,

Figure 2 is a view similar to Figure 1 but showing the chuck in a position to tightly grip the blades or bits to be ground,

Figure 3 is a top plan view of my device as illustrated in Figure 1,

Figure 4 is a transverse vertical sectional view taken on the line 4—4 of Figure 2, and

Figure 5 is a longitudinal vertical sectional view of a modified form of the invention.

In the accompanying drawing, wherein for the purpose of illustration, is shown a preferred embodiment of my invention, the numeral 10 designates the attaching plate of a suitable grinding machine, which plate is formed with an elongated slot 11 and which slot is covered by the base plate 12 embodying a part of my invention. The base plate is preferably formed of a relatively heavy metallic sheet or bar material though any substance suitable for the purpose may be used. It is necessary that the plate be attached to the part 10 of the grinding machine in proximity to the grinding head thereof and, while any suitable means may be used to fixedly attach the base plate to the machine, I have here illustrated the same as being fixedly secured thereto by means of the bolt elements 13. It is to be understood that the mode of attaching the base plate to the machine must, of necessity, be governed by the particular type and make of

the machine to which it is attached. For instance, if the base plate is to be attached to that type of grinding machine known in the art as a side head grinder, it may be necessary to provide the base plate with a suitable shank by means of which it may be adjustably secured in the machine. In any event, it is to be understood that it is within the contemplation of my invention to provide any mode of attachment which is suitable to the particular grinding machine with which the device is associated.

The base plate is here illustrated as being of essentially rectangular formation in plan and as being provided with a flat top surface 14 for receiving the arched support or clamping plate 15. The plate 15 is preferably constructed from a suitable metallic bar material which is inherently resilient in its nature. The bar is normally longitudinally arched and the top surface 16 thereof is formed with a plurality of spaced parallel slots 17. The slots extend through the opposite side edges 18 and 19 of the support and open through the top surface thereof whereby to normally permit the blades or bits 20 to be easily inserted therein. To facilitate the insertion of the blades I have formed each of the slots with outwardly divergent side walls and, as clearly illustrated in the drawing, the slots are uniformly inclined from the vertical so that when the blades are inserted in the slots they will be inclined from the vertical and the upper wall of the slot will incline slightly angularly away from the top surface of the blade. The blades are of standard dimensions and the bottom of each of the slots is of a thickness substantially equal to the thickness of the blade so that the base of the blade will fit snugly therein. The slots are of uniform depth whereby to position the upper working edges of the blades in coplanar relation when a blade has been inserted in each of the slots and the support has been flexed to lie flatly against the flat top surface of the base in the manner illustrated in Figure 2.

As hereinabove described, the base plate overlies the slot 11 in the machine part 10. This slot is provided for the purpose of receiving the enlarged head portion 21 of the bolt elements 22 so that the threaded shank portion of the bolts may be inserted upwardly through the openings 23 in the base and into the registering screw threaded openings 24 in the support. Any desired number of the bolts 22 may be used though I have here illustrated the same as being six in number and as being arranged in pairs at spaced intervals along the length of the support. The

number of the bolts is, however, immaterial in that it is only necessary to use a sufficient number of bolts to hold the support securely and flatly in position on the base plate during the grinding operation. By reason of the fact that the support is longitudinally arched it may be necessary to make certain of the openings 23 in the base of slightly increased diameter to properly accommodate the inwardly inclined bolt elements carried by the ends of the support. In any event, however, the openings should be of lesser diameter than the heads 21 of the bolts.

The instant invention is uniquely adapted to permit a complete set of identical blades to be ground simultaneously. I have particularly in mind a set of bits to be used in wood-working machines though it is to be understood that the invention is in no way restricted to the same. These sets conventionally consist of eight bits which must have identical working faces. For this reason I have illustrated the support as being provided with eight slots though, obviously, any number of the slots may be provided in order that a complete set of blades may be ground in one operation. Heretofore each of the blades comprising the set has been separately ground by hand but this method has many attendant disadvantages in that considerable loss of material usually results due to the difficulty in fashioning the working faces of the bits in identical formation. The hand grinding method of making the sets of blades also requires considerable time and labor.

In carrying out my invention I place the support on the base plate with the threaded openings 24 in registration with the openings 23 in the base plate. The shanks of the bolts 22 are then inserted upwardly through the openings 23 and threaded into the openings 24 of the support. As soon as the bolts have been threaded into the openings a sufficient distance to move the heads thereof into engagement with the under side of the base plate they may be tightened by the use of any suitable tool to flex the support whereby to cause the same to lie flatly against the top surface of the base. The blades are inserted in the slots before flexing of the support and these blades generally comprise one pattern plate which is placed in the endmost slot and a plurality of blanks of sufficient number to complete the set required. When the support is flexed the side walls of each of the slots move toward each other and clamping pressure is applied against the opposite sides of the blades to securely hold the same against displacement. The grinding wheel of the machine is then brought into operative association with the upwardly projecting edges of the blades and, by using the end blade or bit as a pattern, all of the bits may be easily and uniformly shaped.

As soon as the bolts 22 are unthreaded the resilient support will automatically return to its normally arched position whereby to cause the opposite side walls of the slots to spread apart and to release the blades. Both the operation of flexing the support to close the slots and the operation of releasing the same to open the slots may be easily and expeditiously accomplished by the use of a minimum of time and labor.

In Figure 5 I have illustrated a modification of the invention in that the support 15 is provided with only two of the slots 17. If a lesser number of slots is used, as would be the case if only two bits were required to make a complete set, a lesser number of the bolts 22 would be required and Figure 5 has been illustrated as using only

two of the bolts. The support 15 is similarly longitudinally arched and the side walls of the slots are outwardly divergent in the manner described for the first form of the invention.

5 The structural details and mode of use of this form of the invention are so similar to those set forth in connection with the first form of the invention that no further explanation is thought to be necessary.

10 It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. A chuck comprising a base having a flat surface, an arched resilient support having a plurality of spaced slots in its top surface for receiving cutting elements resting upon the mentioned surface of the base, and means for securing the support to the base and for applying a clamping pressure thereto for flexing the same flatly against the said surface of the base whereby to cause the walls of the slots to move into pressed engagement with said cutting elements.

2. The combination as set forth in claim 1 wherein the walls of the slots are outwardly divergent.

3. The combination as set forth in claim 1 wherein the slots are inclined from the vertical and arranged in parallel relation.

4. The combination as set forth in claim 1 wherein the slots are inclined from the vertical and wherein the side walls of each of the slots are outwardly divergent.

5. A chuck comprising a base having a flat surface an arched resilient support having provision for receiving a plurality of elements mounted on the flat surface of the base, and means for securing the support to the base and for applying a clamping pressure thereto for flexing the same flatly against the mentioned surface of the base, the arrangement being such that flexing of the support will cause the same to tightly grip the said elements and to present the edges thereof to be formed in coplanar relation.

6. A chuck comprising a base having a flat surface, an arched resilient support having provision for receiving a plurality of elements mounted on the flat surface of the base, and clamp means operable from the under side of the base having parts extending through the base and coacting with the support so that actuation of the said clamp means will flex the support to cause the same to lie flatly against the surface of the base and to tightly grip the said elements.

7. A chuck comprising a base having a flat surface, an arched resilient support having a plurality of spaced slots in its top surface for receiving cutting elements resting upon the mentioned surface of the base, and clamp means operable from the underside of the base having parts extending through the base and coacting with the support so that actuation of the said clamp means will flex the support to cause the same to lie flatly against the surface of the base whereby to cause the walls of the slots to move into pressed engagement with said cutting elements.

75 WILLIAM E. POWELL.
